CASING MACHINE FOR CIGAR-WRAPPER
LEAVESClarence I. Vellner, Detroit, Mich., assignor to
Air Conditioning Corporation, a corporation
of Michigan

Application June 6, 1935, Serial No. 25,223

15 Claims. (Cl. 131—55)

This invention relates to the conditioning of tobacco leaves adapted to be used as wrapper leaves in the manufacture of cigars.

Tobacco leaves for cigar manufacture have heretofore usually been conditioned by moving the leaves manually in a humidified atmosphere for a period of from three to four hours for Connecticut shade grown leaves, or for an overnight period of from eight to ten hours for Sumatra wrapper leaves. This conditioning operation is usually termed "casing". Casing increases the moisture content of the leaves so as to condition the latter to have the proper elasticity and pliability and thus to facilitate wrapping of cigars, and when properly accomplished, preserves the original color of the wrapper leaves. The Sumatra wrapper leaves, especially, become darkened when moisture is allowed to remain thereon for any material length of time. This collection of moisture on wrapper leaves causes "off-shade" cigars which are thrown out as seconds, and even where a wrapper is darkened uniformly, the impression is given a buyer that he is receiving a strong cigar. For this reason, and also to improve the flavor of cigars, manufacturers pay premium prices for light Sumatra leaf tobacco.

In casing tobacco, it is essential that just the proper amount of moisture be applied to the leaves since the wrapper that is too wet does not possess sufficient elasticity to roll properly, thus reducing production and increasing the number of cigars which have to be rejected as seconds.

It is an object of this invention to improve the art of casing tobacco leaves.

Another object is to provide an automatic tobacco casing machine which applies the correct amount of moisture to wrapper leaves and applies such moisture at all times at correct temperatures in such a manner that the wrapper leaves are not changed from their original color.

A further object is to reduce the time required for casing tobacco leaves.

It is also an object of the invention to direct conditioned air currents within the casing machine in such a manner that the leaves are first separated or spread out and then are drawn through conditioned air currents directed first against one surface of the leaves and then against the opposite surface thereof, and this process repeated throughout the casing operation.

Another object is to render the operation of the casing machine visible so that the condition of the tobacco leaves may be determined at all times

by an attendant and so that the leaves may be removed from the machine at the proper time.

A further object is to prevent condensed moisture from contacting the tobacco leaves during the casing operation.

It is another object of the invention to provide means for controlling the moisture content and temperature of the atmosphere circulated and applied to the tobacco leaves, and gradually to increase both the moisture content and temperature of the circulated atmosphere during the casing process.

It is a further object to apply controlled amounts of moisture at controlled temperatures to all parts of the tobacco leaves and in gradually increasing quantities at gradually increasing temperatures during the casing operation.

Another object of the invention is mechanically to keep the leaves constantly in motion during the casing operation.

A further object is to move the leaves in cycles with tip ends of the leaves foremost, first into a conditioned air current adapted to separate or spread the leaves, then to draw the leaves through similar air currents applied to opposite faces of the leaves while holding the leaves to a carrier in such a manner that the maximum circulation of air is effected through the leaves.

A still further object of the invention is to insure uniform moisture content of all tobacco of the same type case, thus to enable production of uniform numbers of cigars per unit amount of tobacco case.

Other objects, features and advantages will become apparent from the following description and appended claims.

For the purpose of illustrating the genus of the invention, a typical concrete embodiment of tobacco casing machine is illustrated in the accompanying drawings, in which:

Fig. 1 is a longitudinal and vertical section taken substantially centrally through the casing machine;

Fig. 2 is a horizontal section taken substantially on the line 2—2 of Fig. 1;

Fig. 3 is a similar section taken on the line 3—3 of Fig. 1, the conveyor means for the tobacco leaves and other parts being removed to illustrate only the arrangement of the air conditioning ducts;

Fig. 4 is a transverse, vertical section taken substantially on the line 4—4 of Fig. 1;

Fig. 5 is a similar section taken in the opposite direction and on the line 5—5 of Fig. 1;

Fig. 6 is an enlarged, vertical section taken on the line 6—6 of Fig. 2;

Fig. 7 is a fragmentary, horizontal section taken substantially on the line 7—7 of Fig. 1;

5 Fig. 8 is an enlarged, vertical section taken on the line 8—8 of Fig. 2;

Fig. 9 is a fragmentary perspective of an element shown in Figs. 1, 5, and 8; and

10 Fig. 10 is an enlarged view, in side elevation, of temperature control means and automatic setting means therefor, which are adapted to be arranged as indicated in Fig. 1.

Referring to the drawings, and more especially to Figs. 1, 2, and 3, the present automatic tobacco casing machine is illustrated as comprising an insulating box 11 providing a treating chamber 12 therein in which is mounted a Ferris wheel type conveyor 14. The conveyor 14 includes a shaft 15 journaled for rotation in suitable bearings in 20 the side walls of the insulated box 11 and has a plurality of pairs of radially extending and axially opposed arms 16 fixed thereto. The outer ends of each of the arms 16 are provided with inwardly directed studs 17 on which a plurality of racks 20 25 are adapted to be suspended each by a pair of open hooks 21. The racks 20 each include a pair of end plates 22 to which the hooks 21 are fixed and the plates are connected in each instance by two sets of parallel rods 23, the rods of each set also 30 being arranged in triangular relation, as indicated in Fig. 1. Bundles of tobacco leaves, usually termed "hands", each hand usually comprising approximately eighteen leaves of tobacco tied together with a soft stem at the butt end thereof, 35 are hung over each of the sets of rods 23 of racks 20 with the butt ends of the leaves uppermost and the hand divided about in the middle. Approximately fourteen hands are draped over each of the sets of rods 23 of each rack 20, care being 40 exercised in hanging the hands so that the leaves of one hand do not lie over the leaves of adjacent hands. A wire retainer 25, in the form of a closed loop shaped as indicated in Figs. 5, 8, and 9, is then forced downwardly over the butt ends of 45 the hands 24 and over the uppermost rod 23 of each of the sets of rods of racks 20 to lock the hands 24 upon the racks. The Ferris wheel conveyor 14 is adapted to be driven by a motor 26 through a speed reduction unit 27, sprocket gears 50 28 and 30 and a sprocket chain 31 so as to rotate the racks 20 in a circular path within the treating chamber 12. An adjustable idler means 32 may be provided for taking up slack of sprocket chain 31.

55 The hands 24 of tobacco leaves thus secured to the racks 20 are rotated through a series of air currents carrying suspended moisture and indicated generally by the arrows 33, 34, 35, and 36. The direction of rotation of the Ferris wheel type conveyor 14 is indicated by the arrow 37. The hands 24 carried at all times in vertically upright positions by the conveyor 14 move through air currents traveling in different directions so that the hands 24 first meet air currents 34 and 35 60 blowing up from below so as to separate and spread the leaves thereof and are then drawn into a current 33 impinging upon one face of the leaves of hands 24, and finally are drawn through a current 36 impinging upon the opposite faces of the 65 leaves of the hands. As the conveyor 14 rotates, this process is repeated throughout the casing 70 operation.

75 The air is re-circulated through the treating chamber 12 by means of a double turbine type blower 40, indicated in Figs. 1 and 7, which is

provided with an intake conduit 41 and an outlet conduit 42. The turbine 40 is adapted to be driven by means of a motor 43 through the belt means 44 and suitable pulleys mounted on the motor and blower shafts. The intake conduit 41 is 5 divided by means of a longitudinally directed partition 45 into upper and lower sections 46 and 47 and a damper 50 is disposed within the intake conduit 41 so as to control the relative amounts of air passed through the upper or heated section 10 46 and the lower or by-pass section 47 of the intake conduit. The damper 50 is adapted to be automatically controlled and to this end is operated by a motor 51 which is controlled by a thermostat 52, or other suitable temperature 15 responsive means located just beyond an eliminator section 53 arranged within and adjacent the discharge end of outlet conduit 42. A heat interchanger 54 is arranged within the upper section 46 of intake conduit 41 and is under the control of the thermostat or temperature responsive means 52 which also controls a motorized valve 55 arranged in the steam line of the heat interchanger 54. Thus the thermostat means 52 at one temperature limit will serve to turn on steam 20 to the heat interchanger 54 and operate damper 50 so as to close the by-pass section 47 of intake conduit 41 and at another temperature limit will turn off the steam to the heat interchanger and open the by-pass conduit 47. 30

Air is drawn from the upper portion of the treating chamber 12 through the intake conduit 41 of blower 40 and forced through the exhaust conduit 42 and a spray chamber 56 disposed within the latter. Water is supplied to the spray 35 chamber 56 from the city mains and is passed through a steam jacketed coil 57 controlled by by-pass valve means 58 and through a pipe 60 leading to spray chamber 56. Spray heads 61 are disposed in the spray chamber 56 in opposed 40 relation and each is connected by a pipe 62 to an air compressor 63. A solenoid valve 64 is preferably connected in series in the circuit of the compressor motor so that water and air may be turned on through operation of a common switch. 45 The by-pass valve means 58 is set to supply water at a predetermined temperature and need be adjusted only to compensate for seasonal changes in the temperature of water supplied from city mains. Suitable drain connections are led from 50 various sections of the treating chamber 12 to a drain trap 65 to drain moisture which may condense at certain points within the apparatus.

Transparent doors 66 are provided for loading the apparatus and a light 67 is placed within the 55 treating chamber 12 so that an attendant may view the hands 24 of tobacco as the conditioning or casing process is being carried out and determine when to remove the hands 24 from the casing machine. 60

From the spray chamber 56, the air passes through the eliminator section 53 to remove dirt, dust and foreign matter therefrom and then passes through the end of the outlet conduit 42 to outlet or ejector ducts 71, 72, and 73, arranged 65 as indicated in Figs. 1 to 5. The duct 71 leads into the treating chamber 12 at one side and at approximately the same level as that of shaft 15 of conveyor 14, the discharge end of outlet or ejector duct 71 being inclined slightly downwardly so that the air currents 33 leading therefrom are projected in such a direction that the hands 24 are drawn upwardly therethrough during rotation of carrier 14. The ejector duct 72 70 is located adjacent the floor of treating chamber 75 73.

12 and projects air currents 34 and 35 upwardly so as to separate and spread the leaves of hands 24 prior to their being drawn through the air currents 33. The third outlet or ejector duct 5 13 is arranged adjacent the front of the casing machine just above loading doors 66 and projects the air currents 36 upon the opposite faces of the leaves of hands 24 from the faces of the leaves contacted by the air currents 33. As indicated in Figs. 1 and 4, the ducts 12 and 13 are 10 provided with dampers 74 and 75 which control the amounts of air blowing therethrough and which dampers may be set to regulate the flow through the several ejector or discharge ducts. 15 The duct 11 is likewise provided with a damper 16 for regulating the passage of air therethrough. As also indicated in Figs. 1 and 7, additional air may be drawn into the machine through conduits 18 leading through a horizontal partition 20 19, a part of which forms the bottom wall of the intake conduit 41 and through a ventilating grill 29 arranged adjacent the air compressor 63. The additional air is drawn into the machine so that the air pressure within the treating chamber 25 12 will not be below atmospheric pressure due to pressure losses incurred in intake and outlet conduits 41 and 42, blower 40 and discharge ducts 11, 12, and 13. The pressure within the treating chamber is adjustable by varying the amount 30 of additional air drawn into the machine. To this end adjustable slide doors 38 are provided at the intake ends of conduits 18 and these are adjusted preferably so that atmospheric pressure will be maintained within the treating chamber 35 12. Pressures below atmospheric would allow only incomplete casing of the tobacco and pressures too much above atmospheric pressure in chamber 12 would result in too wet tobacco as well as causing losses of conditioned air from the 40 machine.

Referring to Figs. 1, 2, and 6, condensation formed on the shaft 15 of the Ferris wheel conveyor 14, is prevented from dropping on the hands 24 of tobacco by means of a dispenser 11 45 comprising a frame 78, pads 80 and one or more layers of absorbent material, such as cotton cloth 81 wound over the frame 78. This dispenser spreads any water which may drop from the shaft 15 through the cloth layers 81 and pads 50 80 so that moisture in the form of drops will not contact the hands of tobacco leaves during rotation of carrier 14. Condensation formed adjacent the outlet of the ejector ducts 11 and 13 is carried away by means of drain tubes 82 and 55 83 leading to the drain trap 65 and thence to a sewer. A baffle 84, Fig. 1, is provided at the upper portion of the treating chamber 12 to prevent short circuiting of air currents 36 blowing from the ejector duct 13. A thermometer 85 60 is placed in the pipe leading from heat interchanger 57 and by-pass valve means 58 to the spray chamber 56 to indicate the temperature of water delivered to the spray chamber.

Referring to Fig. 10, the thermostat or temperature responsive means indicated at 52 in Fig. 1, will be explained more in detail. This means serves as a heat control regulator and consists of an electric motor 86 adapted to operate under load at a speed of approximately 2700 65 R. P. M. The shaft of the motor 86 is provided with a pinion 87 adapted to drive a gear 88 which has fixed to its shaft a pinion gear 90 adapted to drive a gear 91. The above pinions and gears are preferably of the spur type and the ratio 70 of gears 87 to 88 and 90 to 91 is 1 to 15 in each

instance. The shaft of the gear 91 is provided with a worm 92 adapted to drive a worm wheel 93 and has a gear ratio of 1 to 10. The shaft of the worm wheel 93 has fixed thereto a worm 94 adapted to drive a worm wheel 95 and this unit likewise has a gear ratio of 1 to 10. The shaft of the worm wheel 95 has fixed thereto a beveled pinion 96 adapted to drive a bevel gear 97 at a gear ratio of 1 to 9. Thus the gears 87 to 97, inclusive, afford a gear reduction ratio 10 of 202,500 to 1, so that the motor 86 operating at a rate of approximately 2700 R. P. M. will cause the bevel gear 97 to make approximately two revolutions in a period of 2½ hours. The gear 97 is non-rotatably fixed to the heat adjusting screw 98 of temperature controller 100 which is adjustable and calibrated so that one revolution of the adjusting screw 98 sets the temperature controller for a one degree rise in temperature. The temperature responsive element 101 of the temperature controller 100 is 15 adjustably carried by the screw 98 and adapted to operate a mercury tube switch 102 which in turn controls the electrically operated valve 55 of heat interchanger 54 and also controls the 20 motor 51 of damper 50 to direct air through the heat interchanger 54 or to by-pass the air around the heat interchanger through the conduit section 41 of the blower intake conduit 41. The bevel gear 97 is slidably, but non-rotatably, 25 mounted on the adjusting screw shaft 98 by splining or by a slot and key connection so that the gear may be lowered against the tension of a spring 105 by a manual control knob 106 provided for the purpose of manually adjusting 30 or pre-setting the temperature controller 100. 35

In casing tobacco leaves, the hands 24 are prepared and fastened to the racks 20 as previously indicated. Just prior to the assembling of hands 24 upon the racks 20, the prepared hands are 40 stood butt ends downward in a dipping rack so that about 2 inches of the butt ends are under water at a temperature of approximately 70 degrees F. The butt ends of the hands remain 45 under water for a period of three minutes and are then drained for a period of about three hours before being cased. The hands 24 are then assembled upon the racks 20 and wire retainers 25 snapped into place in such a manner that the retainers are fairly tight over the hands 24. The 50 racks 20 are then hung upon the studs 17 of the rotatable conveyor 14 by means of the hooks 21.

Before starting the casing machine the temperature of the water delivered by spray nozzles 61 is 55 adjusted to 70 degrees F. A blower 40 is then turned on, followed by turning on the spray motor and the doors 66 of the casing machine are kept closed for a period of about fifteen minutes. This is approximately the time required for loading the racks 20. In loading the casing machine, the 60 spray nozzles 61 are turned off, followed by the shutting down of the blower 40. The doors 66 are then opened and rotation of the Ferris wheel conveyor 14 is initiated by means of motor 26 and in the directions indicated by arrows 37. The 65 switch for controlling the motor 26 is preferably located just inside the door 66. The loaded racks 20 are then suspended from studs 17 by means of the hooks 21 during rotation of the carrier 14. An experienced attendant requires only one or two 70 minutes to load the Ferris wheel conveyor and the doors 66 are closed as soon as possible and blower 40 started immediately. The spray nozzles 61 are then turned on one at a time. The temperature of 75 the interior of the casing machine should be

tween 78 and 80 degrees F. when loading the casing machine. The temperature controller 100 is set at 80 degrees F. and the motor 86 started so that the temperature within in the treating chamber 12 will rise at a rate of approximately 2 degrees F. during a 2½ hour period. The heat interchangers are supplied with steam at a pressure of 15 pounds or less, reducing valves being employed to obtain such pressures, when necessary. During the summer months the steam may be turned off altogether.

Various tobaccos require different lengths of time for complete casing, at which condition the tobacco leaves are heavy with moisture but without any free water showing on the leaves when taken from the machine. Sumatra and Java wrapper leaves usually require from two to three hours while Connecticut shade grown wrapper leaves require approximately from one to one and one-half hours. The dampers 74 provided in outlet duct 72 are adjusted so that the leaves of hands 24 are blown apart when passing over the air currents 34 and 35. This adjustment is preferably made with the doors 66 closed while having dry tobacco loaded on the carrier and over the outlet duct 72 with the blower 40 running. The other dampers 75 and 76 may be adjusted as required to give the proper degree of uniformity in the casing operation.

30 During operation of the casing machine, the tobacco making up the hands 24 is moved into the conditioned air currents 34 and 35 as the Ferris wheel conveyor carries the racks 20 over the outlets of the lower duct 72 and is drawn 35 through the air currents 33 and 36 of the racks of the two upper ducts 71 and 73. This arrangement accomplishes the results which were attempted to be achieved by hand manipulation in prior casing practice. The racks 20 hold the tobacco in 40 such a manner as to permit the maximum amount of circulation of air through the tobacco so that moisture is applied to every part of the leaves in a gradual manner. The amounts and temperatures of air and moisture applied to the leaves 45 are readily controllable and the tobacco is kept constantly in motion mechanically while being securely locked on the racks by the wire retainers 25. The moisture content of the tobacco cased by the machine is uniform for each type of tobacco conditioned, thus insuring approximately uniform numbers of cigars per unit weight of leaf tobacco cased without depending upon the skill of an attendant. The original colors of the tobacco cased are retained and the tendency to darken or 50 streak practically eliminated.

As many changes could be made in the above construction and methods and many apparently widely different embodiments and processes of carrying out this invention could be had without 55 departing from the spirit thereof, it is intended that all matter contained in the above description or shown in the accompanying drawings shall be interpreted as illustrative and not in a limiting sense.

60 55 What is claimed is:

1. Apparatus for casing tobacco, comprising in combination a movable carrier for conveying in a circular path hands of tobacco leaves suspended vertically on said carrier, a plurality of ducts arranged at spaced points about said circular path and adapted to direct humidified air in substantially radially inward directions with respect to the center of said circular path, one of said ducts being arranged to direct humidified air in a generally upward direction against said hands to

separate the leaves thereof, other ducts being arranged to direct humidified air against opposite faces of the leaves of said hands, means for moving said conveyor, and means for causing flow of humidified air from said ducts.

2. Apparatus for casing tobacco, comprising in combination a chamber, a movable carrier mounted therein for conveying hands of tobacco leaves suspended at all times vertically thereon, a plurality of ducts arranged to direct humidified air against said leaves alternately in a direction substantially from tip to butt ends of the leaves for separating the leaves of said hands and then against opposite faces of the leaves, means for moving said carrier, means for causing flow of humidified air from said ducts, and means for controlling the temperature of said humidified air.

3. Apparatus for casing tobacco, comprising in combination a chamber, a movable carrier mounted therein for conveying hands of tobacco leaves suspended vertically thereon, a plurality of ducts arranged to direct humidified air against said leaves alternately in a direction substantially from tip to butt ends of the leaves for separating the leaves of said hands and then against opposite faces of the leaves, means for moving said carrier, means for causing flow of the humidified air from said ducts, means for controlling the temperature of said humidified air, and means for operating said temperature control means so as gradually to increase the temperature of the humidified air.

4. Apparatus for casing tobacco, comprising in combination a chamber, a Ferris wheel conveyor mounted for rotation therein, means for rotating said conveyor, means for securing hands of tobacco leaves at all times in vertically suspended positions on said conveyor, means for circulating air through said chamber including a plurality of ducts adapted to discharge currents of air at spaced points around said conveyor and in substantially radially inward direction with respect to the axis of rotation of the conveyor, at least one of said ducts being arranged so as to discharge air in a substantially vertically upward direction for spreading the leaves of said hands, means for adding water to the air circulated through said chamber, means for controlling the amounts and temperatures of water added to said air, means for controlling the temperature of the air and water circulated, and means for gradually increasing the temperature of the circulated air and water to prevent occurrence of a dew point condition within the chamber as the moisture content of the circulated air increases.

5. Apparatus for casing tobacco, comprising in combination a chamber, a movable carrier for hands of tobacco leaves mounted in said chamber, means for moving said carrier, means for circulating air in said chamber including a blower provided with intake and outlet conduits, said outlet conduit being provided with a plurality of discharge ducts adapted to direct air against the hands mounted on said carrier from points spaced around said carrier, a heat interchanger for heating the air circulated by said blower, means for by-passing air around said heat interchanger, means for controlling the relative amounts of air passed through said heat interchanger and by-passed therearound, valve means for controlling the operation of said heat interchanger, means for controlling the operation of said heat interchanger, means for controlling the operation of the means for by-passing

- air around the heat interchanger, and temperature responsive means for controlling the operation of both of the control means for the heat interchanger and for the by-pass means.
5. Apparatus for casing tobacco, comprising in combination a chamber, a movable carrier for hands of tobacco mounted in said chamber, means for moving said carrier, means for circulating air in said chamber including a blower provided with intake and outlet conduits, said outlet conduit being provided with a plurality of discharge ducts adapted to direct air from spaced points around said carrier against the hands mounted thereon, a heat interchanger for heating the air circulated by said blower, means for bypassing air around said heat interchanger, means for controlling the relative amounts of air passed through said heat interchanger and by-passed therewith, valve means for controlling the operation of said heat interchanger, means for controlling the operation of the by-pass means, temperature responsive means for controlling the operation of both the control means for the heat interchanger and for the by-pass means, and means for operating said temperature responsive means so as to cause an increase in the temperature of the air circulated.
7. Apparatus for casing tobacco, comprising in combination a chamber, a movable carrier for hands of tobacco leaves mounted in said chamber, means for moving said carrier, means for circulating air in said chamber including a blower provided with intake and outlet conduits, said outlet conduit being provided with a plurality of discharge ducts arranged at spaced points around said carrier and adapted to direct air against the leaves mounted thereon, a heat interchanger for heating the air circulated by said blower, means for adding water to the air circulated through said outlet conduit, means for bypassing air around said heat interchanger, means for controlling the relative amounts of air passed through said heat interchanger and by-passed therewith, valve means for controlling the operation of the heat interchanger, means for controlling the operation of said by-pass means, temperature responsive means for controlling the operation of both the control means for the heat interchanger and for the by-pass means, and means for operating said temperature responsive means so as to cause an increase in the temperature of the air circulated.
8. Apparatus for casing tobacco, comprising in combination a chamber, a movable carrier for hands of tobacco leaves mounted in said chamber, means for moving said carrier, means for circulating air in said chamber including a blower provided with intake and outlet conduits, said outlet conduit being provided with a plurality of discharge ducts arranged at spaced points around said carrier and adapted to direct air against the leaves mounted thereon, a heat interchanger for heating the air circulated by said blower, means for adding water to the air circulated through said outlet conduit, means for bypassing air around said heat interchanger, means for controlling the relative amounts of air passed through said heat interchanger and by-passed therewith, valve means for controlling the operation of said heat interchanger, means for controlling the operation of said by-pass means, temperature responsive means for controlling the operation of the control means for both the heat interchanger and for the by-pass means, and a constant speed operator for slowly and gradually adjusting the setting of said temperature responsive means for causing a gradual increase in the temperature of the air circulated to prevent occurrence of a dew point condition within the chamber as the moisture content of the circulated air increases.
9. Apparatus for casing tobacco comprising in combination a chamber, a movable carrier for hands of tobacco leaves mounted in said chamber, means for moving said carrier, means for circulating air in said chamber including a blower provided with a plurality of discharge ducts arranged at spaced points around said carrier and adapted to direct air against the hands mounted thereon, a heat interchanger for heating the air circulated by said blower, means for adding water to the air circulated through said outlet conduit, means for bypassing air around said heat interchanger, means for controlling the relative amounts of air passed through said heat interchanger and by-passed therewith, valve means for controlling the operation of said heat interchanger, means for controlling the operation of said by-pass means, temperature responsive means for controlling the operation of the control means for both the heat interchanger and for the by-pass means, means for operating said temperature responsive means so as to cause a gradual increase in the temperature of the air circulated, a heat interchanger for heating the water supplied to the circulated air, and means for controlling the operation of said last named heat interchanger to control the temperature of the water supplied to the circulated air.
10. In a tobacco casing machine, a chamber, means for moistening and heating air and continuously re-circulating such air through said chamber, a Ferris wheel conveyor rotatably mounted in said chamber and including a central shaft, radially arranged arms extending from said shaft and racks carried by said arms for pivotally suspending hands of tobacco leaves at all times in vertical position during rotation of said conveyor, and means disposed about said shaft for preventing water condensed upon said shaft from dropping onto said hands.
11. Apparatus for casing tobacco, comprising in combination a movable carrier for conveying in a circular path hands of tobacco leaves suspended vertically on said carrier, a plurality of ducts arranged at spaced points around said circular path and adapted to direct humidified air in substantially radially inward direction with respect to the center of said circular path, one of said ducts being arranged to direct humidified air in a generally upward direction against said hands to separate the leaves thereof, other ducts being arranged to direct humidified air against opposite faces of the leaves of said hands, means for moving said conveyor, means for causing discharge of humidified air from said ducts, and means arranged adjacent the outlets of said other ducts for draining condensed moisture therefrom to prevent drops of water from contacting said hands.
12. The method of casing tobacco comprising moving hands of tobacco in a path in a treating chamber while maintaining the hands at all times in vertically arranged positions, passing heated and humidified air currents alternately upward through said hands and then against opposite faces of said leaves of the hands during each revolution of said hands.
13. The method of casing tobacco comprising

moving hands of tobacco in a path in a treating chamber while maintaining the hands at all times in vertically arranged positions, passing heated and humidified air currents alternately upward through said hands and then against opposite faces of the leaves of said hands during each revolution of the hands, increasing the moisture content of the humidified air, and gradually increasing the temperature of the humidified air to prevent occurrence of a dew point condition in said chamber.

14. Apparatus for casing tobacco, comprising in combination a treating chamber, a movable carrier mounted therein for conveying hands of tobacco leaves suspended at all times vertically thereon, a plurality of ducts arranged to direct humidified air against said leaves alternately in a direction substantially from tip to butt ends of the leaves for separating the leaves of said hands and then against opposite faces of the leaves, means for moving said carrier, means for causing flow of humidified air from said ducts, means for controlling the temperature of said

humidified air, and means for admitting additional air into the apparatus to maintain substantially atmospheric pressure.

15. Apparatus for casing tobacco, comprising in combination a treating chamber, a movable carrier mounted therein for conveying hands of tobacco leaves suspended vertically thereon, a plurality of ducts arranged to direct humidified air against said leaves alternately in a direction substantially from tip to butt ends of the leaves for separating the leaves of said hands and then against opposite faces of the leaves, means for moving said carrier, means for causing flow of humidified air from said ducts, means for controlling the temperature of said humidified air, means for admitting additional air into the apparatus for raising the air pressure within the treating chamber, and means for adjusting said last named means to vary the quantity of additional air admitted to adjust the air pressure within said treating chamber.

CERTIFICATE OF CORRECTION.

Patent No. 2,097,168.

October 26, 1937.

CLARENCE I. VELLNER.

It is hereby certified that error appears in the printed specification of the above numbered patent requiring correction as follows: Page 5, second column, line 68, and page 6, first column, line 1, claims 12 and 13 respectively, before the word "path" insert closed; and that the said Letters Patent should be read with these corrections therein that the same may conform to the record of the case in the Patent Office.

Signed and sealed this 7th day of December, A. D. 1937.

(Seal)

Henry Van Arsdale,
Acting Commissioner of Patents.

moving hands of tobacco in a path in a treating chamber while maintaining the hands at all times in vertically arranged positions, passing heated and humidified air currents alternately upward through said hands and then against opposite faces of the leaves of said hands during each revolution of the hands, increasing the moisture content of the humidified air, and gradually increasing the temperature of the humidified air to prevent occurrence of a dew point condition in said chamber.

14. Apparatus for casing tobacco, comprising in combination a treating chamber, a movable carrier mounted therein for conveying hands of tobacco leaves suspended at all times vertically thereon, a plurality of ducts arranged to direct humidified air against said leaves alternately in a direction substantially from tip to butt ends of the leaves for separating the leaves of said hands and then against opposite faces of the leaves, means for moving said carrier, means for causing flow of humidified air from said ducts, means for controlling the temperature of said

humidified air, and means for admitting additional air into the apparatus to maintain substantially atmospheric pressure.

15. Apparatus for casing tobacco, comprising in combination a treating chamber, a movable carrier mounted therein for conveying hands of tobacco leaves suspended vertically thereon, a plurality of ducts arranged to direct humidified air against said leaves alternately in a direction substantially from tip to butt ends of the leaves for separating the leaves of said hands and then against opposite faces of the leaves, means for moving said carrier, means for causing flow of humidified air from said ducts, means for controlling the temperature of said humidified air, means for admitting additional air into the apparatus for raising the air pressure within the treating chamber, and means for adjusting said last named means to vary the quantity of additional air admitted to adjust the air pressure within said treating chamber.

CLARENCE I. VELLNER.

CERTIFICATE OF CORRECTION.

Patent No. 2,097,168.

October 26, 1937.
